Specification for Design.

Patented Jan. 26, 1915.

Application filed October 1, 1914. Serial No. 864,539. Term of patent 3½ years.

To all whom it may concern:

Be it known that I, HENRY A. JENNINGS, a citizen of the United States, residing at Bridgeport, county of Fairfield, State of Connecticut, have invented a new, original, and ornamental Design for Portable Electric Lamps, of which the following is a specification, reference being had to the accompanying drawing, forming part thereof.

The figure is an elevation of a portable electric lamp, showing my novel design.

Copies of this patent may be obtained for five cents each, by addressing the "Commissioner of Patents, Washington, D. C."

What I claim is:

The ornamental design for a portable electric lamp, substantially as shown.

In testimony whereof I affix my signature in presence of two witnesses.

HENRY A. JENNINGS.
